UNITED STATES PATENT OFFICE

143,540

DESIGN FOR A PULL TOY

Charles Martin, Chicago, Ill.

Application July 16, 1945, Serial No. 120,734

Term of patent 14 years

(Cl. D34—15)

To all whom it may concern:

Be it known that I, Charles Martin, a citizen of the United States, residing at Chicago, in the county of Cook and State of Illinois, have invented a new, original, and ornamental Design for a Pull Toy, of which the following is a specification, reference being made to the accompanying drawing, forming a part thereof.

In the drawing:

Fig. 1 is a side elevational view of a pull toy showing my new design;

Fig. 2 is another side view of the pull toy shown in Fig. 1 with the eccentric wheels partially rotated; and

Fig. 3 is a top plan view of the pull toy shown in Fig. 1.

I claim:

The ornamental design for a pull toy, substantially as shown.

CHARLES MARTIN.
